CONTROL MEANS FOR DICTATION MACHINES

Hayward K. Mann, South Orange, N. J., assignor to The Gray Manufacturing Company, Hartford, Conn., a corporation of Connecticut

Application March 31, 1942, Serial No. 436,975

4 Claims. (Cl. 179—100.4)

This invention relates to improvements particularly concerned with the control of the amplifier and associated parts as employed in a combined sound recording and reproducing machine such for example as a dictation recording and transcribing machine.

The subject matter of this application, although not limited to such use, is particularly applicable to a dictation machine of the type disclosed in the copending application of Barton A. Proctor and Ferdinand C. W. Thiede, Serial No. 218,082, filed July 8, 1938, now Patent No. 2,296,870, granted September 29, 1942.

A general object of the invention is the provision of a single simply controlled switching device by means of which a plurality of varied interconnections may be established between an amplifier, a microphone, a loudspeaker, a sound recording or cutting head, and a sound reproducing or pick-up head.

A comparable object of this invention and resulting from a combination as referred to above, is to effect simplification in the operation of a dictating machine.

Other and more detailed objects of the invention will be apparent from the following description when taken in connection with the attached drawing.

This invention resides substantially in the combination, construction, arrangement, and relative location of parts as will be described in detail below.

In the accompanying drawing the single figure is a diagrammatic illustration of the elements comprising this invention and their manner of association to secure the objects thereof.

In dictation recording and transcribing machines of some modern types, as for example that disclosed in the above-mentioned application, there is included a multi-stage vacuum tube audio frequency amplifier which serves the purpose of receiving and amplifying the impulses applied thereto by a microphone and supplying those impulses after amplification to the proper magnitude to a sound recording head by means of which representative records thereof are made on suitable record blanks. This amplifier is also employed in the same machine during transcription to receive the impulses produced by the cooperation of a reproducing or pick-up head and the record tablet, and after amplification to supply them to a loudspeaker for recreation as sound waves. This multiple use of the amplifier necessitates suitable switching mechanism which heretofore has been relatively complicated and has required special knowledge on the part of the operator in order to effect the proper connections for the various operations of the apparatus. In accordance with this invention all necessary switching operations are ac-

complished by a single instrumentality in the form of a relay which can be operated by quite simple manipulations on the part of the operator to effect all of the connections necessary to obtain the full operation of the system.

The exact nature of the invention can best be appreciated by describing the mechanism illustrated in the drawing in detail. The reference numeral 5 is employed to indicate the complete multi-stage vacuum tube audio frequency amplifier. No reference to this amplifier in detail will be made since, as will become apparent as the description proceeds, the invention is not concerned specifically with the amplifier, although one suitable form of amplifier has been shown in detail in order to fully understand the relationship of the other parts of the system thereto. The power pack includes a full wave vacuum tube rectifier 3 and associated parts, including a suitable filter network 4. The input of the power transformer for the power pack is connected to the terminals 1, which input in accordance with common practice may be a 110 volt alternating current light system. The power pack transformer is provided with a secondary which feeds the full wave rectifier and an auxiliary secondary which energizes a signal or dial light 6. The negative side of the filter is grounded, as indicated at 2. The common return lead 15 or negative side of the amplifier is grounded as indicated at 14.

The input transformer of the audio frequency amplifier is indicated at 10. Its primary is associated with the terminal board to which is connected a microphone 11, a loudspeaker 12, and a neon warning light 13. One terminal of each of these three devices is connected to the grounded return lead 15. It will be seen that the microphone 11 is directly connected to the primary of the transformer 10. The ungrounded side of the loudspeaker is connected by a wire to a fixed contact in switch 30 which cooperates with the movable blade 20^b of that switch. The ungrounded terminal of the neon warning light 13 is connected by a wire to one terminal of the relay operating coil 21, the other terminal of which is connected to the positive side of the filter 4. The wire from the ungrounded side of the neon light 13 is connectable to ground at 8 through switches 7 and 19. As will be described in more detail later, the switch 7 is associated with the mechanism for alternately operating the recording and pick up heads into engagement with the record, and switch 19 is associated with the clutch or other driving connection between the main power source and the record tablet. It will be seen from the drawing that when switches 7 and 19 are closed, the neon warning light 13 is short circuited, and is extinguished, but under all other conditions, with either or

both of switches 7 and 19 open, the warning light 18 is energized. As will be referred to again later, when switches 7 and 19 are both closed the relay winding 21 is energized, operating the switch 20 from the position shown to its other position.

The reproducing head 17 and the recording head 18 are pivotally mounted on the ends of a link 9 which in turn is pivotally mounted at its center on an adjacent part of the machine. The link 9 has an extension and pointer provided with an operating knob 9' positioned in the actual machine for ready access by the operator. When the link 9 is horizontal and the pointer is in neutral or mid position; both the heads 17 and 18 are out of engagement with the record, the plane of which is indicated by a dash-dot line in the figure. It may be noted that this part of the mechanism is shown in reproducing position, in recording position the pointer will be inclined to the right and switch 7 will be closed by it.

Referring again to switch 20, the uppermost movable blade 20^a thereof cooperates with the fixed contact which is connected to the output transformer 16 of the amplifier. This relay switch also contains a movable blade 20^c which normally engages the lower fixed contact, as shown, which is connected to one of the output anodes of an intermediate vacuum tube of the amplifier, as shown. The upper contact associated with this switch blade is connected to the other output anode of the same vacuum tube and to the output anode of the first vacuum tube. The cathode switch blade 20^c is connected to a point of proper potential in the filter 4 and output transformer 16 has its other terminal connected, as shown, to another point in the filter to provide the proper operating potential therefor. One terminal of the recording head 18 is connected to the movable switch blade 20^a. One terminal of the pick up or reproducing head 17 is connected to the control electrode of the right hand half of the above-mentioned intermediate vacuum tube of the amplifier. The other terminals of the recorder 18 and reproducer 17 are connected by a common lead to the grounded side of the filter. Movable switch blade 20^b is connected to the ungrounded side of a coil forming part of the output transformer 16 as shown.

There is diagrammatically illustrated herein a part of the mechanism by means of which the power from the drive source (not shown) is applied to the record to rotate it as shown in full detail in the above-mentioned application. This mechanism includes an arm 22 pivotally mounted at 23 and connectable to ground by means of a start-stop switch 30. The free end of the lever 22 is provided with a roller 24 which engages the top surface of the record when in the depressed position shown in the drawing. When in its raised position the roller 24 is out of contact with the record. As shown in the above-mentioned application a power driven roller 24' engages the opposite side of the record in line with the roller 24 so that the record is revolved when roller 24 is in down position in order to grip the record between it and the power driven roller. The movable contact of switch 19 is mounted on, but insulated from, the lever 22, and is grounded as shown at 8. The fixed contact of switch 19 is connected to the fixed contact of switch 7, the movable contact of which is connected to the ungrounded terminal of the relay

winding 21. Switch 19 is open when lever 22 is in the depressed position shown and is closed when the lever is in raised position. The lever 22 is mounted so as to remain in either of the two positions mentioned, when actuated to those positions. This lever is actuated to those positions by means of a pair of magnets 25 and 26. One terminal of each of these magnets is connected to a grounded current source 27. The other terminal of magnet 25 is connected by wire 29 to a fixed contact engaged by the lever 22 when depressed. The other terminal of magnet 26 is connected by wire 28 to a fixed contact arranged to engage lever 22 when in raised position.

The operation of this system will now be described in detail. When the power for the system is turned on, energy is supplied to the terminals 1 and dial light 6 is energized indicating to the operator that the power is on. The parts are shown in the position which they assume when the machine is operating to reproduce and so the description of the operation of the machine will be taken up from this point as being the simplest approach. It will be seen from the figure that the stylus of the reproducer 17 engages the record tablet which lies in the plane of the dash-dot line. The stylus of the recording head 18 is off the record, switch 7 is open, switch 19 is closed, relay 21 is deenergized, and arm 22 is down so that its roller 24 is gripping the record tablet between it and the lower power driven roller 24'. If the operator desires to stop the machine he simply momentarily closes switch 30, completing a circuit from ground through that switch, lever 22, wire 29, magnet 25, and current source 27 back to ground. Thus magnet 25 is energized, raising arm 22 so that roller 24 disengages the record tablet and it stops rotating. The upper movement of arm 22 opens switch 19 and also causes the engagement of the lever with the contact connected to wire 28. In the meantime, however, switch 30 has opened since the operation of the mechanism requires only momentary closing of switch 30. To again start the machine, the operator merely momentarily closes switch 30, which in this case completes a circuit from ground through that switch, lever 22, wire 28, magnet 26, and current source 27 to ground. The energization of magnet 26 pulls lever 22 down so that the roller 24 engages the record and it again begins to revolve. Throughout the period when the machine is in use, the power driven roller 24' is rotating continuously. At the end of the reproduction period switch 30 is again momentarily closed to raise lever 22 and link 9 is swung manually to neutral position so that neither the recorder nor the reproducer engages the record.

In order to record, the operator through the agency of knob 9' and the link 9 moves the recorder 18 down so that its stylus engages the record whereupon the reproducer 17 is raised and its stylus disengages the record. At the same time switch 7 is closed, but switch 19 is open, since lever 22 is in raised position. The advantage of this arrangement is that it appears that the worst condition of disturbing electrical feedback occurs if the amplifier is connected when the stylus of the recording head engages the record tablet and the record tablet is stationary. However, with this invention the amplifier is not connected to the recorder because switch 20 remains in the position shown by reason of the fact that although switch 7 is closed, switch 19 is open. In order to record, the operator then momentarily

closes switch 30 which pulls the lever 22 down to the position shown in the drawing in the manner previously described. At this time, however, the closing of switch 19 completes the circuit to the magnet 21, because switch 7 is also closed. Energization of the solenoid 21 shifts switch 20 from the position shown to its other position. At the same time that winding 21 is energized, the neon warning light 13 is short circuited and extinguished, indicating to the operator that the machine is in recording position. The operation of switch 20 to its other position, as mentioned, causes the breaking of the loudspeaker circuit at switch blade 20^b and the making of the recording head circuit at switch blade 20^a, with the result that the recording head is connected to the output of the amplifier at the transformer 16.

Switch blade 20^c disengages its lower contact and engages its upper contact completing the output circuit of the left hand section of the intermediate amplifier tube. The amplifier 5 is now operative with the recording head connected to the output thereof and the microphone connected to the input thereof. The record tablet is in motion hence recording may take place. Whenever the dictator interrupts his dictation for any reason and therefore wishes to stop the machine, he momentarily closes switch 30 to raise arm 22 as previously described. Thus the record tablet stops and the amplifier is disconnected from the recording head because switch 19 opens. Therefore the undesired hum due to feedback cannot occur. Of course every time the motion of the record tablet is stopped the warning light 13 is energized.

At this point it may be noted that the winding 21 is energized from the power pack of the machine. This is a practical feature of the invention in that the relay winding may be a low voltage direct current neon light 13 may be associated therewith. This light may be mounted directly on the microphone and may have its leads therefore built right into the microphone cable without producing any undesired hum. As soon as the apparatus is energized, as mentioned at the beginning of this description of operation, warning light 13 is energized indicating that fact and the fact that the machine is in reproducing position or in neutral position. However as soon as the machine shifts to a condition where it may record, the warning light is extinguished, indicating to the operator that the machine is in recording condition.

It may be noted as not having been mentioned before that the output of the reproducer 17 during reproduction is fed to the right hand half of the intermediate vacuum tube of the amplifier, which in turn feeds the vacuum tube to the right thereof and its output is fed to the loudspeaker through the transformer 16 and switch blade 20^b. Thus during reproduction only the last two tubes of the amplifier are used.

From the above description it will be apparent to those skilled in the art that the subject matter of this invention may be embodied in other physical forms, and combinations, and I do not, therefore, desire to be strictly limited to the disclosure as given for purposes of illustration, but rather to the scope of the claims granted me.

What is claimed is:

1. In a machine of the type described, the combination including a multi-stage vacuum tube amplifier, a power supply means for said amplifier including a rectifier and a filter, a microphone 5 connected to the input of said amplifier, a loudspeaker, a recording head, a reproducing head, a multiple two-position switch, said switch in its normal position connecting the reproducing head to the input of said amplifier and the loudspeaker 10 to the output of said amplifier and in its other position connecting the recording head to the output of said amplifier, and an electro-magnet for operating said switch energized from said power means when the machine is in operation 15 for recording.
2. In a machine of the type described, the combination including a multi-stage vacuum tube amplifier, a power supply means for said amplifier including a rectifier and a filter, a microphone 20 connected to the input of said amplifier, a loudspeaker, a recording head, a reproducing head, a multiple two-position switch, said switch in its normal position connecting the reproducing head to the input of said amplifier and the 25 loudspeaker to the output of said amplifier and in its other position connecting the recording head to the output of said amplifier, an electro-magnet for operating said switch energized from said power means when the machine is in operation 30 for recording, and a warning light connected with said electro-magnet so as to be de-energized whenever said electro-magnet is energized and to be energized whenever said electro-magnet is de-energized.
3. In a machine of the type described, the combination including a multi-stage vacuum tube amplifier having first and second input terminals and a common output, a microphone connected to the first of said input terminals, a recording 40 head, a loudspeaker, a combination switch having a normal position, circuits including said switch in normal position for connecting said reproducing head to the second of said input terminals and said loudspeaker to said common output, a recording head, circuits including said switch when operated from its normal position for connecting said recording head to said common output, and electromagnetic means for operating said switch from its normal to its other 45 position and energized as an incident to putting the machine in operation.
4. In an electro-acoustic machine of the type described, a record support, a recording head, a 50 reproducing head, means for supporting and moving said heads so as to alternatively engage a record when mounted on said support, an electrical amplifier, a loudspeaker, a microphone, circuits including a switch for variously connecting said heads, speaker and microphone to said amplifier, a magnet for said switch, power means for moving said support, and a circuit for said magnet including two switches, one of said last switches being closed by the means for moving 55 said heads when moved to engage the recording head with the record, and the other of said last switches being closed when said power means is operated to cause the record support to move, whereby said magnet is energized to operate the associated switch to connect the microphone to 60 the input of the amplifier.
5. In an electro-acoustic machine of the type described, a record support, a recording head, a reproducing head, means for supporting and moving said heads so as to alternatively engage a record when mounted on said support, an electrical amplifier, a loudspeaker, a microphone, circuits including a switch for variously connecting said heads, speaker and microphone to said amplifier, a magnet for said switch, power means for moving said support, and a circuit for said magnet including two switches, one of said last switches being closed by the means for moving 65 said heads when moved to engage the recording head with the record, and the other of said last switches being closed when said power means is operated to cause the record support to move, whereby said magnet is energized to operate the associated switch to connect the microphone to 70 the input of the amplifier.

HAYWARD K. MANN.
